AUTOMATIC RECLOSED BREAKER SYSTEM

Charles Wilbur Watson, Rocky Point, N. Y., assignor to Radio Corporation of America, a corporation of Delaware

Application February 5, 1938, Serial No. 188,838

11 Claims. (Cl. 175—294)

My present invention relates to a means for automatically restarting electrical devices or for automatically reclosing an electrical circuit.

On electrical devices provided with overload or undervoltage protective devices, it is very desirable to automatically reclose the circuit as soon as the undesirable condition which caused the operation of the protective devices has been cleared. This permits service to be restored with a minimum time lapse. However, within my knowledge, previous devices for automatic circuit reclosure have been so complicated and expensive that manual operation has been mainly relied on in the industry. Therefore, an object of my invention is to provide simple, inexpensive means for automatically reclosing an electrical circuit.

Another object of my invention is to provide an automatic circuit recloser device which will restore service as soon as the undesirable condition which interrupted service has been removed.

Still another object is to provide an automatic circuit recloser device which will, in case the first attempt to restart is unsuccessful, repeat the cycle a predetermined number of times and, thereafter, lock-out automatically.

Briefly, my invention comprises an electromagnetic relay with a plurality of contacts, the first of which closes immediately upon an energization of the relay winding and locks in its energization. This operation is automatically controlled by the removal of the undesirable conditions which caused the circuit breaker to be tripped. A second set of contacts on my device are under control of a time delay device and after a predetermined time close and then reopen the control for the circuit breaker. If this operation of the control circuit is unsuccessful in reclosing the circuit due to the undesirable condition continuing, or otherwise, my device may be adjusted to repeat the cycle either continuously or, after a predetermined number of reclosures, to lock-out automatically, or it may be arranged to lock-out after the first operation.

Referring, now, to the drawings for a more complete disclosure of my invention, Fig. 1 shows diagrammatically one form of my invention; Fig. 2 shows a modification thereof; Fig. 3 shows a further modification of the form of my invention shown by Fig. 2.

Referring, now, to Fig. 1, the device consists of an electromagnetic relay having winding 1 and armature 2. The armature is directly connected to contacts 3 which are closed immediate-

ly after the relay coil 1 is energized. Also connected to the armature 2 through time delay mechanism 4 is a control contact 5. In co-operating relationship with contact 5 is a contact 5' which is supported on an arm 6 which is pivoted at the center. The other end of arm 6 carries contact 7 which cooperates with fixed contact 7'. Contacts 5 and 5' close under control of the time delay mechanism and shortly after these contacts are closed, due to the continued movement of the contact train, arm 6 is moved which causes contact 7 and 7' to break. However, the mechanism is adjusted so that both contacts remain closed for a short interval. This is accomplished by means of a small spring 5! supporting contact 5 and by so adjusting the mechanism that a portion of the operation of the time delay escapement mechanism takes place after contacts 5 and 5' close, but before contact 7 and 7' open.

The typical time delay mechanism for use in my invention includes a spring 41 which is stressed under the influence of the armature 2 of the control relay. This spring causes arm 42 to be moved at a rate determined by clock escapement 43 connected thereto through a rack and pinion mechanism. The operation of contacts 5 and 5' closes the control circuit connected to terminals 14, 15 for the electrical device which is to be restarted and after the desired time delay, which is determined by the spring 5!, contacts 7, 7' open the same control circuit.

A remote control relay B is provided having contacts 8 connected in series with a source of energy and winding 1 of the relay. The winding of relay B is energized through terminals 9, 9 from a circuit in the main device or load which becomes energized when the device is ready to be started. This circuit and details of the main switch are shown in the lower part of the figure and will be explained more fully hereafter. A suitable indicator, alarm or counting device 20 is connected in parallel with relay winding 1 to give an indication of the operation of my device.

45 The operation of my device is, briefly, as follows:

The overload, undervoltage or other protective devices are arranged to operate interlock switches 10 whenever the correct conditions exist for operation of the main device or load, and when it is desired to energize the load. These switches may be operated by safety doors around the load, temperature responsive devices on bearings, etc. The interlock circuit also contains a switch 71 operated by magnet 72 whenever the load draws

more than a predetermined current. This circuit supervises the operation of the load and causes disconnection to take place under abnormal conditions. The recloser control switch 16 is left open and the main device or load energized in a normal manner by means of the "on" push-button 18. Closure of normally open switch 18 closes a circuit from 13' through normally closed switch 19, switch 18, arm 6, contacts 7, 7, terminal 15, recloser coil 73, switch 71, interlock switches 70 and back to 13, the other side of the supply line, thus actuating recloser 73. This actuation closes contacts 74 and 75. Closure of contacts 75 energizes the actuating coil 68 of main switch 60, thus energizing the load 61 from the alternating current supply. Main switch 60 is of a conventional type having moving contacts 62, 63 engaging stationary contacts 62' and 63' and carried by an actuating arm 64. Arm 64 also causes back contact 65 to engage contacts 65' when the main contacts are opened.

Closure of contacts 74 closes a locking circuit for coil 73 through a circuit which may be traced from 13' through switch 19, terminal 14, contacts 74, coil 73, switches 71, 70 and back to 13. As soon as main switch 60 closes terminals 9, 9 are automatically de-energized by the opening of back contacts 65, 65' on the main switch 60. The recloser control switch 16 is then closed and the device is ready for operation. In case switch 71 is opened due to load 61 drawing excessive current through coil 71, or any of the interlock switches are opened, the locking circuit for coil 73 is opened and main switch 60 opens closing contacts 65, 65'. As soon as switches 70 and/or 71 return to normal, a circuit is closed from line 83' through contacts 65 and 65', terminal 9, winding of relay B and lamp 10, terminal 9', switches 71, 70 and thence to line 83. Energization of this circuit and lighting of lamp 10 constitutes a signal that the load circuit is in proper condition to be energized from the supply line. Contacts 8 of this relay B close and supply power to the coil 1 of the reclosing relay. This causes contacts 3 to close and also causes an energization of the indicating device 20. The time delay mechanism 4 will be started in operation at the same time. Contacts 3 hold the reclosing relay coil 1 energized as long as the lock-out 17 and recloser control switches 16 remain closed. This circuit may be traced from terminal 13 through coil 1, switch 17, contacts 3, switch 16, switch 19 to terminal 13'.

When the desired amount of time has elapsed, as determined by the escapement 43, contacts 5, 5' close while contacts 7, 7' remain closed for a short interval. This closes the circuit around the "on" push-button 18 completing the circuit between the terminals 14, 15, which recloses the main switch 60 as heretofore described for manual operation of switch 18. Contacts 7, 7' then open but coil 73 is by that time locked in by closure of contacts 74 provided the lock-out switch 17 and recloser control switch 16 remain closed. If the lock-out switch 17 is closed it will thus be seen that the device will make a single attempt at reclosure and then remain locked out until the control switch 16 is opened by manual or automatic means, thus breaking the locking circuit for winding 1 of the recloser except in the case of a complete power failure, in which case it will repeat its cycle. A failure of the power supply will cause the main switch to open due to de-energization of coils 68 and 73.

When the recloser has locked out it is put in

readiness for another operation by simply opening and then closing the control switch 16, either by manual or automatic means. This breaks the locking circuit established through contacts 3 allowing armature 2 to drop back. If the lock-out switch 17 is left open the reclosing device will re-cycle itself each time terminals 9, 9 are energized. This will give a series of single timed reclosures without lock-out each time the main switch 60 connected to the load is opened.

Referring, now, to Fig. 2, which is similar to that shown in Fig. 1, except that a contact 3' cooperating with contact 3 is arranged on a movable arm similar to that employed with respect to contacts 5 and 7. The end of the arm opposite contact 3' carries a contact 11 cooperating with a fixed contact 11'. This construction replaces the lock-out control switch 17, shown in Fig. 1. In this modification control button 18 is arranged to maintain the circuit closed as long as operation is desired. In case the main load is de-energized due to the operation of protective devices associated therewith, or due to a power failure, the terminals 9, 9 will, as before, be re-energized at the proper time, control relay will close its contacts 8 energizing the recloser relay coil 1 through a circuit from terminal 13 and including control switch 16, relay coil 1, contacts 8, the control buttons 18, 19 and thus 25 back to the power supply terminal 13. Contacts 3, 3' immediately close, short circuiting the control relay contacts 8 and locking in the recloser relay coil 1. Recloser coil 73 is also energized through a circuit extending from 13' through 30 manually closed switch 19, switch 18, contacts 11, 11', arm 6, contacts 7, terminal 15, coil 73, switches 71 and 70 and back to terminal 13, thus 35 immediately reclosing switch 60. The contacts 11, 11' open a short interval after contacts 3, 3' 40 have closed which prevents any further energization of coil 73 until contacts 5, 5' are closed. This completes the first immediate reclosure.

When the desired amount of time has elapsed for the second attempt at restarting as regulated 45 by the time delay mechanism 43, contacts 5, 5' close while contacts 7, 7' remain closed for a short interval, as before. This again energizes the circuit for coil 73 effecting a second reclosure in case the first one has been unsuccessful. Contacts 7, 7' then open after a short interval preventing any further attempts at reclosure as long as the control switch 16 remains closed, except in the case of a complete power failure. The recloser has now reached the end 55 of its time cycle and is locked out.

To return the recloser to its normal ready position it is necessary to open and then close the control switch 16 if the main switch 60 is closed. If the main switch 60 is off, the control 60 switch is opened, the main switch 60 closed with push-button 18, as described before, and the recloser control switch thereafter closed to place the recloser in operation.

The modification shown in Fig. 3 is a further 65 modification of that shown in Fig. 2 in that there has been added time delay relay 21 with its coil in parallel with the recloser coil 1 and its contacts 52 arranged in series with the recloser control switch 16. The time delay may be provided by a clockwork escapement similar to escapement 4 if desired. With this arrangement the circuit is immediately interrupted after any desired time following its first operation, thus recycling the recloser through the previously described operations automatically. The form of

my invention shown in Fig. 1 may also be similarly modified.

A further modification of any of the forms of my invention shown in the previously discussed figures may include a mechanical latching device on the recloser to stop its operation after any desired number of operations.

While I have described my invention in some detail I do not wish to be limited to the particular embodiments shown but intend to include all modifications within the scope of my invention.

I claim:

1. An automatic circuit recloser comprising an electromagnet, means under control of protective devices associated with a load for energizing said electromagnet, a locking circuit for said electromagnet, means responsive to the operation of said electromagnet for energizing said locking circuit, a time delay mechanism actuated by said electromagnet and means responsive to the operation of said time delay mechanism for closing a control circuit for energizing said load, a relay connected in parallel with said electromagnet and having its contacts arranged to momentarily de-energize said electromagnet a predetermined time after the operation of said last mentioned means whereby the recloser will repeat its cycle of operation.

2. An automatic circuit recloser comprising an electromagnet, means under control of protective devices associated with a load for energizing said electromagnet, a locking circuit for said electromagnet, a first pair of contacts in said locking circuit actuated by said electromagnet, a time delay mechanism actuated by said electromagnet, a second pair of contacts responsive to the operation of said time delay mechanism for closing a control circuit for energizing said load, a third normally closed pair of contacts in series with said second pair and responsive to the operation of said time delay mechanism for opening said control circuit after a predetermined time.

3. An automatic circuit recloser comprising an electromagnet, means under control of protective devices associated with a load for energizing said electromagnet, a locking circuit for said electromagnet, a first pair of contacts in said locking circuit actuated by said electromagnet, a time delay mechanism actuated by said electromagnet, a second pair of contacts responsive to the operation of said time delay mechanism for closing a control circuit for energizing said load, a third normally closed pair of contacts in series with said second pair and responsive to the operation of said time delay mechanism for opening said control circuit after a predetermined time and a relay connected in parallel with said electromagnet and having its contacts arranged to momentarily de-energize said electromagnet a predetermined time after the operation of said last mentioned means whereby the recloser will repeat its cycle of operation.

4. An automatic circuit recloser comprising an electromagnet, means under control of protective devices associated with a load for energizing said electromagnet, a locking circuit for said electromagnet, a first pair of contacts in said locking circuit actuated by said electromagnet, said first pair of contacts being also arranged to close a control circuit for energizing said load, an auxiliary normally closed pair of contacts in series with said first pair and actuated thereby for opening said control circuit, a time delay mechanism actuated by said electromagnet, a second pair of contacts responsive to the operation of

said time delay mechanism for closing said control circuit, a third normally closed pair of contacts in series with said second pair and responsive to the operation of said time delay mechanism for opening said control circuit after a predetermined time.

5. An automatic circuit recloser comprising an electromagnet, means under control of protective devices associated with a load for energizing said electromagnet, a locking circuit for said electromagnet, a first pair of contacts in said locking circuit actuated by said electromagnet, said first pair of contacts being also arranged to close a control circuit for energizing said load, an auxiliary normally closed pair of contacts in series with said first pair and actuated thereby for opening said control circuit, a time delay mechanism actuated by said electromagnet, a second pair of contacts responsive to the operation of said time delay mechanism for closing said control circuit, a third normally closed pair of contacts in series with said second pair and responsive to the operation of said time delay mechanism for opening said control circuit after a predetermined time, and a relay connected in parallel with said electromagnet and having its contacts arranged to momentarily de-energize said electromagnet a predetermined time after the operation of said last mentioned means whereby the recloser will repeat its cycle of operation.

6. A control mechanism for association with circuit breakers, said mechanism including a circuit which when closed causes a closing of the circuit breaker, a second circuit which when closed indicates an operative condition of the load connected to said breaker and relay means responsive to a closed condition of said second circuit for energizing an electromagnet and locking an energizing circuit for said electromagnet, a time delay mechanism actuated by said relay and means responsive to the operation of said time delay mechanism for closing for a predetermined time said first mentioned circuit.

7. A control mechanism for association with circuit breakers, said mechanism including a circuit which when closed causes a closing of the circuit breaker, a second circuit which when closed indicates an operative condition of the load connected to said breaker and relay means responsive to a closed condition of said second circuit for energizing an electromagnet, a first pair of contacts for said electromagnet, a time delay mechanism actuated by said electromagnet, a second pair of contacts responsive to the operation of said time delay mechanism for closing said first circuit and a third pair of contacts actuated by said second pair of contacts for opening said first circuit.

8. A control mechanism for association with circuit breakers, said mechanism including a circuit which when closed causes a closing of the circuit breaker, a second circuit which when closed indicates an operative condition of the load connected to said breaker and relay means responsive to a closed condition of said second circuit for energizing an electromagnet, a first pair of contacts actuated by said electromagnet, a time delay mechanism actuated by said electromagnet, a second pair of contacts responsive to the operation of said time delay mechanism for closing said first circuit and a third pair of contacts actuated by said second pair of contacts for opening said first circuit, said first pair of contacts being arranged to energize a locking circuit for said electromagnet.

9. A control mechanism for association with circuit breakers, said mechanism including a circuit which when closed causes a closing of the circuit breaker, a second circuit which when closed indicates an operative condition of the load connected to said circuit breaker, an electro-magnet, means responsive to a closed condition of said second circuit for energizing said electro-magnet, a first pair of contacts arranged to be closed by said electro-magnet and to energize a locking circuit therefor, a time delay mechanism actuated by said electro-magnet, a second pair of contacts responsive to the operation of said time delay mechanism for closing said first named circuit, a third pair of contacts in series with said second pair of contacts and actuated thereby for opening said first named circuit whereby an impulse of predetermined length is impressed on said circuit.

10. A control mechanism for association with circuit breakers, said mechanism including a circuit which when closed causes a closing of the circuit breaker, a second circuit which when closed indicates an operative condition of the load connected to said circuit breaker, an electro-magnet, means responsive to a closed condition of said second circuit for energizing said electro-

5 magnet, a locking circuit for said electro-magnet, means responsive to the operation of said electro-magnet for energizing said locking circuit, a time delay mechanism actuated by said electro-magnet and contact means connected to and responsive to the operation of said time delay mechanism for closing said first named circuit for a predetermined time.

11. A control mechanism for association with circuit breakers, said mechanism including a circuit which when closed causes a closing of the circuit breaker, a second circuit which when closed indicates an operative condition of the load connected to said circuit breaker, an electro-magnet, means responsive to a closed condition of said second circuit for energizing said electro-magnet, a locking circuit for said electro-magnet, means responsive to the operation of said electro-magnet for energizing said locking circuit, a time delay mechanism actuated by said electro-magnet and contact means connected to and responsive to the operation of said time delay mechanism for closing said first named circuit for a predetermined time, and a switch in said locking circuit for disabling said locking circuit.

CHARLES WILBUR WATSON.
